SCOOPING APPARATUS FOR MINE SHAFTS

Robert C. Sights, Las Vegas, Nev.

Application October 7, 1954, Serial No. 460,929

3 Claims. (Cl. 214—95)

The present invention relates to excavating devices and more particularly relates to an apparatus for excavating mine shafts, well shafts, and the like and for cleaning, widening or deepening said shafts once the same have been sunk.

The primary object of the present invention is in the provision of a shaft excavating apparatus comprising an excavating shovel or bucket pivotally supported by a frame with operating means for raising and lowering the frame, adjusting the lateral positioning of the frame relative to a shaft wall and tilting the excavating bucket which operating means is carried by the frame.

An important object of the invention, ancillary to the primary object, is in the provision of an excavating bucket supporting frame having a working platform thereon supporting a winch for raising and lowering the frame by winding and unwinding a supporting cable from the winch which winch and frame cooperate to guidingly support the supporting cable relative to the frame whereby the frame will at all times be urged to a position of alignment with the supporting cable whereby the frame will be positively urged toward one wall of the excavated shaft in accordance with the position of entrance of the supporting cable from its supporting source relative to the top of the shaft.

A further object of the invention is in the provision of hydraulically extensible cylinder and piston assemblies carried by the bucket supporting frame or yoke and operable from the working platform which act in conjunction with the cable guiding means of the yoke for adjustably positioning the yoke relative to the side wall of the shaft toward which the yoke is normally urged.

A further object of the invention is in the provision of a hydraulically operable extensible means interconnecting the excavating bucket in the yoke for controllably tilting the excavating bucket about the yoke.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a side elevational view of the excavating apparatus of the present invention disposed for operation in a shaft;

Figure 2 is a front elevational view of the excavating apparatus;

Figure 3 is a side elevational view of a portion of the apparatus disclosing the excavating shovel or bucket in position for scooping earth from the bottom of the shaft to deepen the same;

Figure 4 is a view similar to Figure 3 disclosing the bucket in a second position lifting earth from the bottom of the shaft;

Figure 5 is a perspective view of the disconnected excavating bucket and its supporting frame or yoke; and

Figure 6 is a top view of the working platform mounted on the excavating frame disclosing the operating mecha-

2

nism on this platform for controlling the apparatus therefrom.

Referring now to the drawings in detail, the excavating apparatus is designated in its entirety by the numeral 10 and as shown in Figure 1 is disposed for operation in a mine shaft or the like 12.

The apparatus itself comprises essentially an excavating bucket 14 carried between the arms of a supporting frame or yoke 16 on suitable trunnions 18 whereby the bucket or shovel may be swung to various operating positions relative to the yoke 16.

The frame or yoke 16 comprises a pair of parallel arms 20 which converge toward one another adjacent their upper ends as at 22 to form a bight portion.

Trunnions 18 are attached to the arms 20 adjacent the lower ends thereof and project inwardly between the arms through apertures 24 in the sides of the excavating scoop or bucket 14.

Between the upper ends of the yoke arms 20 the lower end of a vertically rising standard 26 is disposed and rigidly attached thereto.

Intermediate its ends on the parallel portions thereof, the arms 20 are provided with a supporting member 28 extending therebetween and attached at its ends thereto which supporting member in turn carries a rearwardly extending working platform 30.

A pair of spaced lugs 32 project forwardly from the supporting member 28 and a hydraulic cylinder 34 is carried pivotally between these lugs.

From the end of the cylinder 34 projects a hydraulically actuated plunger 36 which at its free end is pivotally secured to a pair of spaced lugs 38 which project upwardly from the back wall of the excavating bucket 14. With this arrangement, it will be seen with reference to Figures 1, 3 and 4 particularly that upon extension and retraction of the cylinder plunger 36 the excavating bucket 14 may be pivoted about the frame 16 from a scooping to a lifting and thence to a dumping position.

In order to adjustably position the excavating apparatus 10 relative to one of the walls of the shaft 12, the lower ends of the frame or yoke arms 20 have rigidly attached thereto hydraulic cylinders 40 which extend perpendicularly to the arms 20 in parallel relation to one another. From the rearward ends of cylinders 40 project hydraulically actuated plungers 42 having heads 44 at the free ends thereof adapted to engage a wall of a shaft 12 and force the apparatus outwardly away from such wall.

To give added utility to the laterally adjusting means created by the hydraulic cylinders and plungers 40, 42, the frame is provided with a novel cable guide arrangement thereon whereby the frame will always maintain a vertical position in movement toward vertical alignment with the supporting source of the supporting cable of the apparatus. The vertical standard 26 of the frame 16 forms a portion of this guide arrangement by virtue of a cable guiding pulley 46 mounted at the upper end thereof.

The other portion of this guidingly supported means comprises a winch 48 mounted on the working platform 30. The suspending cable 50 usually enters the shaft at an angle to the shaft. This cable 50 passes through the guide pulley 46 and its support at the upper end of the standard 26 and the frame 16 and is thence wound upon the winch 48 at its lower end portion with the portion of the cable between the winch 48 and the guide pulley 46 being maintained in substantial parallelism with the frame 16 of the apparatus or machine 10.

A suitable hydraulic motor 52 mounted on the platform 30 and operable therefrom operates the winch 48 to wind and unwind the cable 50 on and from the winch respectively whereby the excavating machine will be raised

and lowered within the shaft at the will of the operator on the working platform 30.

To operate the hydraulically extensible means for tilting the bucket 14 and for adjustably positioning the frame relative to the wall of the shaft, suitable hydraulic operating apparatus and connecting lines are provided on the platform 30. This construction will be most clearly apparent from an examination of Figure 6 wherein there is shown a pneumatic fluid conduit 54 which may lead to a suitable surface reservoir, the lower end of this conduit opening into a suitable air motor or the like 56 for operating the hydraulic pump 58 which is connected by means of hydraulic line 60 to a hydraulic accumulator 62 and through relief valve 64 and hydraulic line 66 to a fluid storage tank 68.

Valves 70, 72 and 74 connect respectively through lines 76 and 78 to the accumulator 62 and the storage 68.

Lines 80 and 82 interconnect valve 74 with one of the laterally positioning cylinders 40 for extension and retraction of the plunger 42 in response to actuation of the valve 74.

Lines 84 and 86 interconnect valve 70 with the other lateral adjusting cylinder 40 for operating the plunger 42 of this cylinder.

Fluid lines 88 and 90 interconnect the valve 72 with the bucket tilting cylinder 34 for operation of the bucket 14 between its dumping, lifting and scooping positions.

In the operation of the device, the platform 30 is provided with a seat 92 thereon as shown in Figure 1 for enabling an operator to operate the controls for the winch and the hydraulically extensible mechanism while giving the operator in addition a clear view of the portion of the shaft in which the apparatus is operating.

Earth is scooped from the bottom or sides of the shaft upon the operation of the excavating bucket or scoop 14 and then dumped into a bail or bucket 94 for elevation to the surface for dumping.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. A shaft excavating apparatus comprising a yoke and an excavating bucket, said yoke including a bight portion and a pair of spaced arms, said bucket being pivotally

carried between said arms, a working platform supported by said yoke between said arms above said bucket, a winding drum on said platform having a supporting cable wound thereon, guide means on said yoke cooperating with said winding drum for maintaining a portion of the supporting cable parallel thereto for a portion of the length of the yoke, extensible means carried by said yoke arms for engaging the wall of a shaft within which the apparatus is disposed, extensible means interconnecting said bucket and said platform for controlling the tilt of said bucket relative to the yoke, means rendering said winding drum operable from said platform for raising and lowering the apparatus, and means carried by said platform for actuating said extensible means.

- 15 2. A shaft excavating machine, said machine comprising an excavating scoop supporting frame, an excavating scoop pivotally carried by said frame, means on said frame for guidingly attaching a suspension cable thereto at longitudinally spaced points therealong whereby the machine will be urged toward parallelism with the wall of a shaft within which it is disposed, extensible means fixedly mounted on said frame for positioning the frame relative to a wall of a shaft, and extensible means interconnecting said bucket and said frame, and a working 20 platform carried by said frame, operating means on said platform for raising and lowering said frame and actuating said extensible means, said operating means including a cable winding winch on said platform for raising and lowering said frame on its suspension cable, said frame 25 comprising a pair of spaced, generally parallel arms interconnected by a bight portion at their upper ends, a vertical standard extending upwardly from said bight portion and having a cable guide at the upper end thereof, said cable guide and said winch comprising said guidingly attaching means.

3. The shaft excavating apparatus of claim 1 and a seat on which an operator is adapted to rest, and means securing said seat to said platform.
